[57] CLAIM

The ornamental design for a combined oil can display and dispenser rack, as shown and described.

DESCRIPTION

FIG. 1 is a front elevational view of a combined oil can display and dispenser rack showing my new design; FIG. 2 is a partial sectional view taken along line 2—2 of FIG. 1;

FIG. 3 is a top plan view thereof; and

FIG. 4 is an enlarged partial sectional view taken along line 4—4 of FIG. 3.

Fig. 2
